Primary Examiner — Manpreet S Matharu*Assistant Examiner* — Rebecca Tsehay(74) Attorney, Agent, or Firm — Tommy SF Wang; Wang IP Law Group, P.C.(57) CLAIM

The ornamental design for a lighter, as shown and described.

DESCRIPTION

FIG. 1 is a perspective view of a lighter in a closed position showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another front view thereof in an opened position. The broken lines in the drawings depict portions of the lighter and form no part of the claimed design.
